CLAIM

I claim the ornamental design for a “multi-function band”, as shown and described.

DESCRIPTION

FIG. 1 is a perspective view of the multi-function band; FIG. 2 is a front view of the multi-function band FIG. 1; FIG. 3 is a back view of the multi-function band of FIG. 1; FIG. 4 is a left side view of the multi-function band of FIG. 1;

FIG. 5 is a right side view of the multi-function band of FIG. 1; FIG. 6 is a top view of the multi-function band of FIG. 1; FIG. 7 is a bottom view of the multi-function band of FIG. 1;

FIG. 8 is a front perspective view of the multi-function band in a condition of use; FIG. 9 is a front view of the multi-function band of FIG. 1 in a condition of use;

FIG. 10 is a front perspective view of the multi-function band in a condition of use; and,

FIG. 11 is a side view of the multi-function band in a condition of use.

Broken lines illustrate environmental features and form no part of the claimed design.
